UNITED STATES PATENT OFFICE

164,780

ELECTRICAL COOKING UNIT

Andrew S. Knapp, St. Louis, Mo., assignor to
Knapp-Monarch Company, St. Louis, Mo., a
corporation of Delaware

Application November 27, 1950, Serial No. 13,137

Term of patent 14 years

(Cl. D81—10)

To all whom it may concern:

Be it known that I, Andrew S. Knapp, a citizen of the United States, and a resident of the city of St. Louis, State of Missouri, have invented a new, original, and ornamental Design for an Electrical Cooking Unit, of which the following is a specification, reference being had to the accompanying drawing, forming a part thereof, in which:

Figure 1 is a perspective view of an electrical cooking unit, showing my new design; and

Figure 2 is a side elevational view thereof.

The side not shown in Figures 1 and 2 is substantially plain.

I claim:

The ornamental design for an electrical cooking unit, substantially as shown and described.

ANDREW S. KNAPP.
